UNITED STATES PATENT OFFICE.

GUSTAV N. MEVES, OF DAVENPORT, IOWA.

OPERATING MECHANISM FOR POWER-ACTUATED WASHING-MACHINES.

1,022,691.

Specification of Letters Patent.

Patented Apr. 9, 1912.

Application filed March 10, 1911. Serial No. 613,635.

To all whom it may concern:

Be it known that I, GUSTAV N. MEVES, a citizen of the United States, and a resident of Davenport, in the county of Scott and State of Iowa, have invented certain new and useful Improvements in Operating Mechanism for Power-Actuated Washing-Machines; and I do hereby declare that the following is a full, clear, and exact description thereof, reference being had to the accompanying drawings, and to the characters of reference marked thereon, which form a part of this specification.

This invention relates to improvements in motor driven operating mechanism for washing machines and the like of that kind of machines embracing a main operating or stirrer head shaft in the tub for agitating the clothes in the wash water and to which may be imparted a rotary reciprocatory motion, and relates also to mechanism associated therewith for operating a secondary shaft or element, such as the roller shaft of a wringer mounted on or associated with a washing machine.

The invention consists in the matters hereinafter set forth and more particularly pointed out in the appended claims.

In the drawings,—Figure 1 is a plan view of a washing machine embodying my improved operating mechanism. Fig. 2 is a side elevation thereof with parts broken away. Fig. 3 is a rear elevation of the machine. Fig. 4 is a front elevation thereof with parts broken away. Fig. 5 is a detail of a joint by which the two parts of the operating shaft pitman may be detachably fastened together.

As shown in the drawings, the tub 6 is provided with the usual swinging lid 7 that is hinged by the hinges 8 to a fixed or non-rising portion 9 of the tub top. Said tub may be supported on the usual legs 10. Extending downwardly through the swinging lid is an operating shaft 17 which carries at its lower end within the tub a stirrer head or dolly 18 (Fig. 4). Said shaft is mounted in a suitable bearing 20 carried by the swinging lid and the shaft is provided at its upper end above the lid with a pinion 21 which meshes with an internally toothed gear-sector 22 that is pivoted by a stud 23 to the lid to swing horizontally and is provided with an extension 24. Said extension 55 may be socketed at its end to receive a hand operating lever 25 by which the sector may

be swung horizontally to impart rotary reciprocatory motion to the operating shaft. The hand operating lever 25 may be connected to the socketed end of the extension 24 by means of a set screw 26. The extension 24 of the sector gear is connected by a pitman 27 with a rotary worm gear wheel 28 that is rotatively mounted on a stud 29 which is fixed to a bracket 30 that is attached to the tub at the non-rising side of the top wall thereof, said bracket having a depending portion which fits about the upper end of the circular wall of the tub and a short flange 31 which fits upon the non-rising portion of the tub top, as shown in Figs. 1 and 3 and is attached thereto by bolts.

32 designates a motor which is supported on a horizontal shelf or platform 32^a of the bracket 30 and is provided with a shaft 33 that is rotatively mounted in bearings 34, 34 of said bracket. Said motor shaft 33 is provided at its opposite ends beyond its bearings with worms 35, 36 (Fig. 2). The worm 35 meshes with the worm gear wheel 28, and the proportions of the worm gear wheel 28 and the worm 35 is such as to reduce the high speed of the motor to a suitably low speed for driving the rotary reciprocatory operating shaft 17 through the pitman, rocking gear sector 22 and pinion 21.

The worm 36 of the motor shaft meshes with a vertically arranged worm wheel 39 that is loosely mounted on a shaft 40 that is rotatively mounted at one end in a bearing 40^a carried by a hood or guard 41 for the worm wheel 39, which is made integral with or attached to the bracket 30. Said shaft is mounted at its other end in the upright standards 42 of a wringer that is fixed to the rear side of the tub in any suitable manner. The shaft 40 constitutes a secondary shaft that is driven by the motor and constitutes, as herein shown, the shaft for one of the wringer rolls 43, 44 the shaft of the coating roll 44 being geared to the driven roll shaft by the gears 45 arranged in a familiar manner. The said worm wheel 39 is adapted to be clutched to the shaft 40 to drive the latter through the medium of a clutch sleeve 46 that is slidable and non-rotative on the shaft 40 and has a toothed end adapted to engage the toothed end of a complementary clutch member 47 that is fixed to the worm wheel 39. The said clutch sleeve 46 is

adapted to be shifted into engagement with the clutch member 47 of the wringer by means of a shifter lever 48 that is pivoted to a downturned member 49 of a bracket 50 attached to the wringer frame and extending laterally therefrom. The said shifter lever is provided with a lug 51 adapted to engage notches in a locking segment 52 on the arm 50 whereby to lock the clutch sleeve in either of its positions. The resiliency of the shifter lever permits the locking lug to be released from and to be held in engagement with the notched segment. The pitman 27 that connects the worm gear 28 with the extension 24 of the operating sector 22 is provided with a joint by which the members may be separated in order to permit the swinging lid 7 to be swung backwardly. This joint comprises, as herein shown, a socket piece 56, shown best in Fig. 5, that is loosely connected to the worm wheel 28 by the stud 57 and has an inwardly opening socket to receive the outer end of the inner link member, said latter link member being fixed in the socket by means of a screw 58. The members of the jointed pitman thus made are separated by releasing the screw 58 and withdrawing the pitman member 27. Obviously other suitable means may be employed for releasably connecting the members of the pitman to permit the swinging cover to be raised. The pitman is connected to the gear sector extension by means of a pivot stud 59 over which the apertured end of the inner pitman member 27 fits, the parts being held together by the key shown in Fig. 1, or otherwise. When the operating shaft 17 is to be actuated by hand the pitman is disconnected at the stud 59. When the machine is operated by power the hand lever 25 may be disconnected from the gear sector extension at the joint 26, which may be made generally like the socket joint 56 before described. The said worm wheel 28 may be protected by a casing 60 which may be bolted to suitably flanged parts of the bracket 30, as indicated at 61. Preferably the worm gear casing or guard will be arranged to cover the geared periphery of the worm gear wheel, as indicated in Fig. 1, so as to permit the members of the connecting pitman 27 to be separated in all positions of the pitman relatively to the worm gear wheel. In the operation of the operating mechanism described, the motor acts through the worms 35 and 36 at the opposite ends thereof to rotate the worm wheels 28 and 39, the former imparting a swinging motion to the gear sector 22 and therethrough a rotary reciprocal motion to the operating shaft 17. The worm wheel 39 is rotated continuously in one direction and operates, when the clutch sleeve or spool 46 is engaged with the clutch member 47 on the hub of said

worm wheel 39, to rotate the shaft 40 and the wringer rolls 43, 44. When the clutch sleeve is in the position shown in Figs. 3 and 4 the wringer rollers are inoperative. A collar 46' on the shaft 40 limits the movement of the clutch sleeve away from the clutch member 47. By employing a reversible motor the wringer rolls may be turned in either direction, either while operating the operating shaft 17 or when the operating mechanism is disconnected from said shaft through the separable operating pitman 27 described. Thus the wringer and operating shaft may be driven either simultaneously or independently by the motor, and either may be separately actuated by hand.

The arrangement shown constitutes an exceedingly compact and efficient driving mechanism for the operating shaft of a washing machine and the wringer shaft or other like secondary operating shaft, the use of the worm gears permitting the high speed of the motor to be reduced to a practicably low speed for operating the dasher shaft and the wringer.

In order that the shaft 33 may be operated when no electrical power is available to operate the motor 32, or otherwise, the said shaft may be rotated through the medium of a crown pulley 65 that is fixed to the shaft 33 which is adapted to be operated from a pulley belt that may be operated by a gas engine or-like motor, as best shown in Figs. 1 and 2.

The upper wringer roll shaft is provided with a short, detachably affixed crank 68 in order to turn the wringer rolls backwardly to unroll material, as small pieces, that may become wound around the rollers. The said crank may be protected by the casing 69 that is hinged at 70 to the adjacent wringer standard 42 and may be held in the upper dotted line position shown in Fig. 4 by means of the dog 71 shown in Fig. 4. If it be desired to operate the wringer by hand, the lower shaft of the wringer roll may be formed with a threaded end 73 to receive a regulation crank to operate the wringer by hand.

The construction described is capable of variations within the spirit and scope of the invention, and the invention is not limited to the illustrated details except as hereinafter made the subject of specific claims.

I claim as my invention:

1. Operating mechanism for washing machines and the like comprising, in combination with a body, a primary operating shaft mounted thereon, a pinion on said shaft, a gear meshing with the pinion, a worm wheel adapted to be connected to the gear, a secondary operating shaft, a worm wheel adapted to be connected to and operate the secondary operating shaft, a motor and a

motor shaft provided with two worms, one meshing with the worm wheel that is operatively connected to the primary operating shaft and the other with the worm wheel 5 of the secondary operating shaft, with means for connecting the said worm wheels to the respective shafts which they operate, and for disconnecting them therefrom, to permit said shafts to be operated either 10 simultaneously or independently.

2. Operating mechanism for washing machines and the like comprising, in combination with a body, an operating shaft capable of rotary reciprocatory motion, a worm 15 wheel operatively connected therewith for imparting rotary reciprocatory motion to said shaft, a wringer operating shaft, a worm wheel connected thereto, and a motor provided with a shaft having two worms, 20 each meshing with one of said worm wheels.

3. Operating mechanism for washing machines and the like comprising, in combination with a body, an operating shaft capable of rotary reciprocatory motion, a worm 25 wheel operatively connected therewith for imparting rotary reciprocatory motion to said shaft, a wringer operating shaft, a worm wheel connected thereto, a motor provided with a shaft having two worms, each meshing 30 with one of said worm wheels, means for disconnecting the operating shaft from its worm wheel, and a hand device for actuating said operating shaft when disconnected from said worm wheel.

35 4. Operating mechanism for washing machines and the like comprising, in combination with a body, an operating shaft capable of rotary reciprocatory motion, a worm wheel operatively connected therewith for 40 imparting rotary reciprocatory motion to said shaft, a wringer operating shaft, a worm wheel connected thereto, a motor pro-

vided with a shaft having two worms, each meshing with one of said worm wheels, and a clutch device for operatively connecting 45 the wringer shaft to and disconnecting it from its worm wheel.

5. Operating mechanism for washing machines and the like comprising, in combination with a body, an operating shaft capable 50 of rotary reciprocatory motion, a pinion on said shaft, a swinging gear sector meshing with said pinion, a bracket attached to said body near its top, a motor mounted on said bracket and provided with a shaft having a 55 worm, a worm wheel meshing with said worm and a pitman pivoted eccentrically to the worm wheel and pivoted to said gear sector.

6. Operating mechanism for washing machines and the like comprising, in combination with a body, an operating shaft capable 60 of rotary reciprocatory motion, a pinion on said shaft, a swinging gear sector meshing with said pinion, a bracket attached to said body near its top, a motor mounted on said bracket and provided with a shaft having a 65 worm, a worm wheel meshing with said worm, a pitman pivoted eccentrically to the worm wheel and pivoted to said gear sector, 70 said pitman embracing two separable members adapted to be detachably locked together by a joint device and a hand lever detachably connected to the swinging gear 75 sector.

In testimony, that I claim the foregoing as my invention I affix my signature in the presence of two witnesses, this 24th day of Feby. A. D. 1911.
